UNITED STATES PATENT OFFICE.

ROBERT CUMMING ANNAND, OF SOUTH SHIELDS, ENGLAND.

APPARATUS FOR CASTING CURVED STEREOTYPE-PLATES.

No. 887,372.

Specification of Letters Patent.

Patented May 12, 1908.

Application filed January 17, 1907. Serial No. 352,695.

To all whom it may concern:

Be it known that I, ROBERT CUMMING ANNAND, of South Shields, England, have invented certain new and useful Improvements in Apparatus for Casting Curved Stereotype-Plates, of which the following is a specification.

This invention aims to provide improved apparatus whereby semi-circular or curved stereotype plates can be rapidly produced.

More particularly the improvements apply to power driven machinery for automatically casting or automatically casting and finishing such plates, but as will be apparent hereafter certain of the improvements described may be used in curved stereotype casting or casting and finishing apparatus operated partly or entirely by hand.

In apparatus as hitherto used for the production of semi-circular stereotype plates it has not been possible to clamp or fasten the matrix to the solid concave part or shell of the casting mold, so that it can remain in this position while the desired number of plates are being cast and removed. The usual practice is to arrange the casting mechanism so that the matrix with the side gages is drawn out of the casting box attached to the newly cast plate and the matrix has to be stripped from the plate and reset in position in the casting back. As this has to be done each time a plate is cast it consumes much valuable time and greatly reduces the output of the machine.

A leading feature of the invention is the provision of means whereby any desired number of semi-circular or curved stereotype plates can be cast and stripped in succession from a matrix clamped or fixed in a rigid continuous casting shell, without injury to the matrix. This is effected by bending the cast plate inwards on the mandrel to a sufficient extent to enable it to be stripped by the mandrel from the matrix, leaving this fixed in the casting shell.

The invention further comprises means for thus bending the cast plate and stripping it from the matrix.

A further part of the invention consists in clamping or securing the top, bottom and side gages in a semicircular or curved casting box so that they will retain the matrix in the casting position while the plate is bent inwards on the mandrel and withdrawn

therein from the casting shell. Such bending of the plate on the core may be effected by constructing the core so that it can be collapsed after the plate has been cast, a sufficient connection between the cast plate and the core being provided to cause the plate to partake of the collapsing motion and thus move away from the matrix to enable it to be stripped therefrom with the core when this is moved out of the casting box or shell. Or a non-collapsible core may be employed and means may be provided whereby when the core is moved out of the casting box after the plate has been cast, the plate is at first delayed from following its motion so that clearance is created between the core and casting box to allow of the plate being bent inwards on the core, this bending being effected as the core moves out of the casting shell.

The invention further comprises the combination with a stationary casting shell and a reciprocating boring bed, of a movable core adapted to be rolled, rotated, or swung with the cast plate adhering thereto out of the casting position in a casting shell direct into the boring bed, the plate being deposited by the core into the boring bed which comes opposite to or at a lower level than the casting box.

The invention further consists in details of construction and combinations of parts which will be hereinafter fully explained in detail.

In the accompanying drawings:—Figures 1 to 15 illustrate a machine constructed in accordance with the invention for automatically casting and finishing semicircular stereotype plates. The melting pot and pump and their position with respect to the machine are shown in Figs. 7 and 8. For the sake of clearness they are omitted in the other figures. Fig. 1 is a side elevation of the machine. Fig. 2 is a part plan of the machine looking in the direction of the arrow A, Fig. 3. Fig. 3 is an end elevation of Fig. 1 looking on the end at which the main driving gear is situated. Fig. 3^a is a detail longitudinal section on a larger scale of the cam drum and reciprocating boring shell. Fig. 4 is a detail sectional end elevation showing the reciprocating boring bed and boring and delivery cylinders together with the means for reciprocating the boring bed. Fig. 4^a is a detail end elevation showing the boring shell 23 in its boring position under the boring cylinder 47.

with the tracks 51^a and 56 hereafter referred to registering. Fig. 5 is a section on line B—B, of Fig. 1. Fig. 6 is a separate view in end elevation illustrating mechanism for automatically stopping the machine at the end of each cycle. Figs. 7, 8, 9 and 10 illustrate the mechanism for operating the pump at the proper period to supply molten metal to the casting box, Figs. 7 and 8 being views of the general lines of the machine in side elevation and plan respectively, and Figs. 9 and 10 detail views on a larger scale and at right angles to each other of this mechanism. Figs. 11 and 12 are detail views of the collapsible mandrel shown in the foregoing figures, Fig. 11 being a part longitudinal rear elevation and Fig. 12 an end elevation. Fig. 12^a is a detail section showing the manner in which connection is provided between the cast plate and core to allow of bending the plate and carrying it from the casting box to the boring shell. Figs. 13 and 14 are detail views in sectional side elevation and plan illustrating means for clamping the matrix in the casting shell. Fig. 15 is a diagrammatic view illustrating the mode of stripping the cast plate from the matrix, delivering it into the boring shell and breaking off the jet. Figs. 16 and 17 are a part longitudinal section and an end elevation illustrating a modified form of collapsible core. Fig. 18 is a part sectional view corresponding to Fig. 5, showing this form of core applied to the same machine with the necessary modification of the mechanism for operating this core. Fig. 19 is a diagram showing the mode of separating the newly cast plate from the matrix and delivering it by the core into the boring shell by the modified mechanism of Fig. 18. Fig. 20 is a similar view to Fig. 18 illustrating another means of bending and stripping the plate from the matrix while employing a non-collapsible mandrel. Fig. 20^a is a sectional detail showing the fixed stopper bar 197 on the core 181. Fig. 21 is a corresponding plan. Fig. 22 is a similar view to Fig. 20 showing the core removed from the mold and the plate bent. Fig. 22^a is a detail view illustrating the projections 206 formed on the plate. Fig. 23 is an end elevation similar to Fig. 20 and showing the method of bending and stripping the plate applied to a casting machine operated by hand.

Referring to Figs. 1 to 15, the machine illustrated comprises a continuous casting shell in which the matrix is firmly fixed, a melting pot with a pump, a boring and trimming frame and delivery mechanism, the whole adapted to produce and deliver completely finished stereo plates.

The machine provides the following automatic mechanism:

Means for removing the newly cast plate from the casting shell direct to a boring shell 22 in which it remains till trimmed along its straight edges and bored. Trimming includes the breaking off of the jet.

Means for supplying the right quantity of molten metal at the proper time to the casting box, thereby casting a plate.

Means to cause the aforesaid boring shell to move under the cutters which trim the straight edges of the newly cast plate, and then to stop under a revolving blade which bores the plate.

Means to cause the plate to revolve about its axis of curvature after having been bored so as to pass a second set of cutters which trim the circular edges and finally to deliver the finished plate on to a suitably placed table.

Means to stop the whole mechanism after the completion of a plate.

The arrows on the drawings indicate the direction of motion of the parts.

I will first describe the general construction and arrangement of the machine and afterwards explain in detail the means whereby the core is collapsed and operated to bend and strip the plate from the matrix and the means for clamping the matrix in the casting box.

The machine comprises four large frames 1, 2, 3, 4. Frame 3 supports brackets 5, 6, 7 which carry the main driving gear. This consists of fast and loose pulleys 8 and 9 on the driving shaft 10. This latter is geared up to a countershaft 11 by toothed wheels 12, 13 on the respective shafts. On the driving shaft 10 is cut a worm 14 which drives a worm wheel 15 on the shaft of the boring and delivery cylinder described later. On the countershaft 11 are loosely mounted miter wheels 16, 17 meshing with a miter wheel 18 keyed on the shaft 19 of the cam drum 20 (see Figs. 1, 2 and 3). The miter wheels 16, 17 are driven alternately in opposite directions by a clutch 21 sliding on keys on the shaft 11 and automatically operated at the proper period by a cam groove 21^a formed in a toothed wheel 63 and arranged to operate the clutch 21 through a roller 66 pinned to a bell crank lever 67 mounted on the frame 3 and the forked lower end of which moves the clutch alternately into engagement with the miter wheels 16, 17 so that the miter wheel 18 and drum 20 are driven alternately in opposite directions.

22 is the shell of the casting box bolted to the frames 1 and 2 which encircle it at each side.

23 is the boring shell consisting of a semi-circular receptacle lined with zinc to receive the plate from the core and adapted to be reciprocated parallel with the casting shell 22 and so as to come opposite thereto at the proper times.

The matrix is clamped in the casting shell 22 and a collapsible core 41 is adapted to be rolled or swung alternately from the boring

shell 23 into the casting shell 22 for casting the plate and from the casting shell into the boring shell to deposit the cast plate. To enable the plate on the core to strip from the fixed matrix without injuring the same, the core is collapsed before it leaves the casting box, sufficient connection being provided between the core and the cast plate that this latter shall be bent inwards by the collapsing core to enable the plate to strip from the matrix.

The boring shell 23 is at a lower level than the casting shell. It slides on upper and lower members of the frame 4 and is reciprocated by the cam drum 20 upon which it rides by means of bearings 24, 24 (Figs. 2 and 5) bolted to keeps 25, 25. Further support is provided by the strut 26 which takes part of the heavy strains exerted in boring.

27, 27 (Fig. 5) are ordinary wedge adjustments for the boring bed to compensate for the wear of the sliding parts.

The mechanism which controls the movements of the cast plate until it is deposited by the core into the boring shell is all centered on the frames 1 and 2 and is driven from a pinion 28 keyed on the shaft 19 of the cam drum through a set of reducing gears 29, 29^a, 30, 31, 32, the last of which is keyed on 30 a shaft 33 at the casting shell side of the machine and serves at the same time as a crank disk, having an equal throw with another crank disk 34 mounted on the shaft 33. As the drum 20 is driven alternately in opposite directions through clutch 21, the crank disks 32, 34 have an oscillating motion (amounting to five-eighths of a revolution each way in the machine illustrated). This motion is transferred by the links 35 to the shaft 36 of the collapsible core which is thus made to oscillate about the central shaft 37 to which it is connected at each end by levers 38, 38. A balance weight 39 is attached to the shaft 37 by arms 40, 40.

45 While the shaft 36 oscillates, the collapsible core 41 revolves, this motion being produced by the meshing of the gear/wheels 42, 42, keyed at each end to the shaft 36, with the segmental racks 43 bolted to the frames 1 and 2. Guides or bearing surfaces 42^a, 43^a may be provided if desired on the toothed wheels and racks to prevent them engaging too deeply the guides 42^a on the spur wheels running on the guides 43^a on the racks which 55 are struck from the same center as the racks.

By means of the combined motion of rotation and translation thus imparted to the core, the plate is stripped from the matrix when the core is collapsed as described later, and the plate is carried by the core and deposited in the boring bed; the combined motion of rotation and translation further enables the jet to be broken off in the manner hereinafter described.

65 The reciprocating motion is imparted to

the boring shell 23 by means of a spiral groove 44 formed in the surface of the drum 20 in which works a roller 45 carried by the boring shell. The drum 20 being rotated alternately in opposite directions as described, the boring shell is driven from end to end of the frame 4 with periods of rest at each end, these being provided for by concentric portions 44^a of the groove 44 in conjunction with the action of the clutch 21. Tools or cutters disposed in the usual way in boxes 46, 46 (Fig. 2) above the path of the boring shell trim the straight edges of the plate as the boring shell slides under them after receiving the plate from the core.

47 (Figs. 1 and 4) is a boring and delivering cylinder mounted concentrically with the boring shell at the outer end of its travel. This cylinder is driven continuously while the machine is working the worm 14 meshing 85 with the worm wheel 15 on the shaft 48 of said cylinder which is mounted in bearings 49, 50 formed respectively in the frame 4 and in a bridge 51 connected to the two sides of the frame 4. The cylinder 47 carries a boring knife 52 and an automatically retractable driver bar 53 at opposite sides and is formed with segmental ribs 54 which strengthen the part and serve to support the plate during the trimming of its circular edges and its delivery. The mechanism is arranged and the speeds are regulated so that the boring shell moves from its position of rest opposite the casting box to its position of rest under the boring cylinder 47 while the boring knife describes the arc C, Fig. 4. 55 is an end gage on the boring cylinder 47 and which may be longitudinally adjustable by any convenient means to provide for plates of different widths of page. A semicircular lip 56 is provided on 105 the boring shell 23, which lip keeps the plate in position in the shell while this is traveling, and coacts with the gage 55 to guide the plate as this revolves to have its curved edges trimmed. This trimming is performed by 110 tools 57, 57, of the usual kind, used for trimming the curved edges of semicircular stereotype plates. One of the tools may be adjustable longitudinally of the boring cylinder 47 to suit different sizes of pages.

58 is a stopper bar arranged to slide inwards on the upper member of the frame 4 at the end opposite the casting shell and 59 is a stopper bar similarly arranged to slide on the frame 4 at the trimming and delivery end of 120 the machine. The bar 58 coacts with two fixed stopper bars 60 bolted to the lower member of the frame 4 to hold and strip the plate into the boring shell 23 from the core 41 when this swings to deliver over the plate 125 into the boring shell and the bars 60 also prevent the plate from sliding out of the boring shell.

The stereo plate is cast with small abutment faces at each end as will be explained 130

with respect to Figs. 13 and 14, these projections being situated at about the line where the jet of the cast plate begins, so that shoulders are formed at each side of the plate. The core swings and rolls the plate into the boring shell when the stopper bar 58 is retracted, the abutment faces on the plate rolling clear of the bars 60 and coming up under or behind the inner corners 60^a of these bars when the plate is in the boring shell, the jet being then located between these bars. Here the jet is broken off before the boring bed 23 begins to slide away, so that the plate is then free to slide in the boring bed to the boring end of the machine in which movement the left hand stopper bar 60 (Fig. 2) prevents the plate slipping out of the boring bed by gravity. The edge of the delivery table 61 is formed as a stopper bar to serve a similar purpose at the other end of the machine, at which end the sliding stopper bar 59 serves to hold the plate in the boring shell during the boring operation. The stopper bars 58 and 59 are operated to engage and release the plate at the proper times through the medium of a cam 62 secured to a toothed wheel 63 running on a stud 64 in the frame 4 and driven by a pinion 65 keyed on the shaft 48 of the boring and delivery cylinder so that it revolves continuously while the machine runs. The cam 62 by means of a roller 68 and lever 69 imparts rocking motion to the shaft 70 which works on bosses 71, Figs. 2 and 3, cast on the frame 4, and thence by levers 72 to the stopper bars 58, 59 which have projecting bosses 73 connected to the levers 72 by a stud and slot connection indicated at 74 in Figs. 3 and 5. The stopper bars 58 and 59 are slid in and out at the proper times on the frame 4 so that their forward edges come over the upper edge of the cast plate in the boring shell.

The bars 58, 59 are guided in their sliding motion by T-pieces 75 screwed to the frame 4 and passing through slots 76, the edges of which they overlap, so that the bars when slid forward can hold the plate rigidly in position in the boring shell in the respective positions thereof, that is to say when the plate is being stripped from the core at the right hand end of Fig. 2 and when it is being bored at the left hand end. The retractable driver bar 53 on the boring cylinder acts in conjunction with the stopper bar 59 and that formed by the edge of the delivery table 61 to manipulate the plate in the boring and trimming of the curved edges. While the shell 23 is sliding with the plate into the boring position the driver bar 53 is describing arc D, Fig. 4, but it is retracted and describes this arc with a smaller radius than that of the plate, so that it clears it. The bar 53 is automatically projected and retracted as follows:—77 are inclined slots in the bar 53 adapted to slide over bolts 78 by

which the bar is attached to the wing 79 of the boring and delivery cylinder 47. 80 is a pin passing through an inclined slot 81 in 79 and screwed to the bar 53. 82 is a spring-pressed rod sliding in holes in the ribs 54 and engaged by the pin 80 which also works in the slot 83 in a block 84 fixed on the rod 82. It will be seen that a movement of rod 82 to right or left of Fig. 2 will project or retract the bar 53. This is shown in the projected position with the spring 85 compressed. It is always held in this position when describing arc C, the spring rod being kept pushed back during this portion of the revolution of 47 by a semi-circular track 51^a provided on the bridge 51 for the end of the spring rod. For the arc D a similar operation takes place when the shell 23 is in the boring position, the track for the end of the spring rod being provided by the semi-circular lip 56 which then forms a continuation of the track on the bridge 51. In any other position of the boring shell the spring 85 is free to push the rod outwards so that while describing arc D the bar 53 is retracted, its outer edge coinciding with that of the wing 79.

On reference to Figs. 2 and 4^a, it will be seen that when the boring shell 23 is in its end position under the boring cylinder 47 the semicircular track 51^a on the bridge 51 registers with the track formed by the semi-circular lip 56 on the boring shell 23, so that a circular track is formed which keeps the spring pin 82 pressed back during the rotation of this pin with the boring cylinder. 100

When the boring shell is in the boring position under the boring cylinder and the driver bar 53 is projected, the knife 52 on the boring cylinder bores the inside of the cast plate in the first half of the revolution (arc C) 105 and the projected driver bar 53 then comes against the straight edge of the plate and, in describing the arc D, pushes the plate out of the boring shell on to the ribs 54 of the boring cylinder as shown at J, J, Fig. 3, the cutters 57 trimming the curved edges as the plate rotates.

There are gaps and projections 86, 86^a in the driver bar 53 corresponding to projections and gaps 87, 87^a on the stopper bar 59 115 and 88, 88^a on the edge of the delivery table 61. This arrangement enables the driver bar 53, when projected, to clear the stopper bar 59 and table 61 while driving the plate round.

The machine is automatically stopped when the finished plate has been pushed on to the ribs 54 as explained or it can be stopped by hand at any moment desired. This is effected by the mechanism shown in Fig. 6 for throwing the driving belt from the fast pulley 8 to the loose pulley 9. 89 is the striking lever carrying bell fork 90 and keyed on the spindle 91 sliding with a feather in bosses 92 of the brackets 5 and 6. The end of the spindle 130

carries a finger 93 which engages a block 94 on the cam 62 in each revolution thereof. The gear wheel 63 and cam 62 may make one revolution in the complete cycle of the machine and the block 94 then pushes the finger 93 and spindle 91 to the right and throws the belt on to loose pulley 9 and the machine stops, the block 94 being by this time just clear of the finger, so that the striking lever 10 can be moved to the "on" position by hand. As the finger is clear of the block at every moment of the cycle except when the plate is being rotated out of the boring shell to deliver it as explained, the machine can be stopped and restarted by hand during any of the trimming processes if desired.

The casting box is supplied with molten metal from an ordinary form of melting pot 95 and pump, Figs. 7 and 8, the details of 20 which are well understood, the pump being operated to pump the metal into the casting box 22 through an arm 95^a by the descent of a weight 96 suspended from a steel rope 96^a and attached to the piston-rod of the pump. 25 The steel rope passes round three pulleys 97, 97 to a tripping mechanism shown separately on a larger scale, Figs. 9 and 10, Fig. 9 including a portion of the frame 1 and the oscillating shaft 33, while Fig. 10 is an end 30 view of Fig. 9 with the driver 98 omitted. The driver 98 is secured to the shaft 33 by a set screw and it carries two pins 99 and 100.

The rope is secured to a grooved pulley 101 which runs free on the shaft 33 adjacent 35 to the driver 98 and has a rectangular piece 10^a let into its circumference, which piece serves as an anchor for the rope and as a stop, enabling pin 100 to drive the pulley in the direction of the arrow K. The catch 40 102 works on a pin 103 screwed into frame 1 and has a spring 104 which tends to press it into the position shown in dotted lines, Fig. 10. As the driver 98 rocks with the shaft 33 the pin 100 drives the pulley 101 round by 45 the piece 101^a and thus winds up the rope and raises the weight 96, until anchor piece 101^a is caught by the catch 102. On the return of the driver with the shaft 33 the pin 99 pushes back the catch 102 to the position 50 shown in full lines and causes it to release anchor piece 101^a, whereupon the weight descends, turning the pulley till the anchor piece strikes pin 100 which will now be again in the position shown in Fig. 10.

55 I will now proceed to describe the details of the machine whereby the matrix is secured in the casting box, the plate temporarily bent so as to be cleared from the matrix before moving out therefrom, and 60 whereby the jet is automatically broken off in the boring shell 23 by the return of the core therefrom.

The method of fixing the matrix in the shell is shown in Figs. 13 and 14. 105, 105 65 are loose side gages disposed in the casting

shell 22, these being preferably arranged to overlap the margins of the matrix about an inch and being inserted in the shell 22 by a semi-circular feather 105^a with which they are each formed, these engaging in grooves 70 in the shell and preventing the side gages from slipping out when released. Any desired number of similar grooves may be provided in the shell to allow the gages to be set for plates of different widths. 75

Portions of the main frames 1 and 2 are shown in Fig. 14 and through these are threaded spindles 106 107 on which are centered grippers 108 109 to hold the straight edges of the matrix 110 which is thus gripped 80 against the shell 22 at M and N along its straight edges, and between the end gages and the shell at its curved edges. Gripper 109 also serves as a stopper bar, completely filling the gap between the shell and the core 85 when this is in casting position, and together with the end gages forming a metal-tight box only open at the top. Gripper 108 is a casting having a channel 111 for circulating cooling water in the known way and fitted 90 with a steel gripping bar 112 running the full length of the shell 22 and fixed to the gripper 108 at each end by screws 113. Also screwed to the gripper 108 are the ends 114 of the mouth piece, which is completed by the 95 wedge-shaped part 115 fastened to the core- 41 (Figs. 3 and 5) and extending across the core. The ends 114 of the mouth-piece abut against the ends of the side gages 105 and lock these in position, causing them to grip 100 the matrix. The grippers 108 109 are locked in-position to grip the matrix and lock the side gages by 108, by means of eccentrics 116 117 working in forks 118 119 attached to the respective grippers. Eccentric 116 is held 105 by brackets 120 carried by the shell 22 and is operated by a handle 121 having a facing 122 formed to abut against a facing 123 on the shell. By throwing the handle over, the eccentric rocks the fork and gripper 108 into 110 or out of its locking position and the facings 122 123 are so arranged that when the gripper has been rocked into gripping position the handle abuts against 123 and locks the gripper 108 in position. The gripper 109 is 115 arranged to be opened and locked in the same way by the eccentric 117 the bearings of which are in the main frames 1, 2, the eccentric 117 being operated by a handle 124 with a facing 125 coacting with a facing 126 on the frame 1. The ends 114 of the mouthpiece project inwards a short distance beyond the usual bevel on the end gages 105 (see Fig. 14) so that small triangular abutment faces 127 are produced at the sides of the jet. These 125 faces serve as before explained to abut against the corners of the stopper bars 60, 60, and prevent the plate slipping out of the boring shell.

I will now describe with reference to Figs. 130

11 and 12 in conjunction with Figs. 3 and 5 the construction and operation of the collapsing core 41 whereby the plate is bent clear of the matrix and rolled out of the casting shell into the boring shell. This core is made in two segments 41, 41^a, hinged at 128, the hinge consisting of two parts 129, 130 attached respectively to the upper and lower segments with respect to which they 10 are circumferentially adjustable by being arranged to slide in grooves 131 in which they can be bolted, so that the adjacent edges of the two segments at 41 and 41^a may be set up into contact to compensate for wear or 15 when otherwise required. 132 is a pin formed on the hinge member 130; this pin has one part of circular section, the center of which is 128, projecting into the hinge member 129, and the other part of elongated section 20 132^a, so as to have a proper bearing surface as it slides in a slot 133 in a bracket 134 supported by the shaft 36 and revolving therewith. This bracket operates links 135, 136, each centered at one end on the bracket 25 while, the other end works over eccentric bushes 136 on the studs 137. The eccentricity of the bushes 136 provides adjustment so that on the operation of the controlling mechanism the segments may be forced 30 apart more or less as may be required.

It will be understood that the above description refers to one end of the core, the mechanism being duplicated at the other end of the core.

35 The shaft 36 and brackets 134 can move in the direction of the slots 133 and by this movement the studs 137 and consequently the segments are moved closer together or further apart. The expansion of the core 10 takes place against the action of springs 138 provided at each end of the core and placed between one of the segments and the washers 139 of spring rods 140 connected to the other segment by pins and eyes 141. 142 is a gravity catch provided at each end of the core and which works between the bracket 134 and a pin 143, and falls into engagement with a nose 144 on the bracket when the core has delivered the plate into the boring shell and 45 expanded, so that the core is then prevented from collapsing. 145 is a groove formed in the segments of the core near the hinge joint, and adapted to be filled with asbestos or like packing so that if any metal should leak past the joint it will be stopped by the packing and not interfere with the proper working of the segments. The core has attached to it the wedge shaped piece or lip 115, Figs. 3 and 5 (omitted in Figs. 11 and 12) which abuts 50 against the mouth-piece ends 114 of the gripper 108 and closes the pouring space at the front when the core is in casting position. 146 is a steel knife edge of the usual kind inserted in the core just behind the wedge shaped piece 115 and extending across and

projecting slightly above the same so as to produce a small sharp angle or recess extending across the jet while the edge of the gripper bar 112 is adapted to form a corresponding sharp angle across the opposite 70 face of the jet at the line of breakage so as to facilitate breaking off of the jet. The core is further formed with the usual parallel grooves into which the metal runs to form the ribs on the inner face of the cast plate, 75 but the grooves in the core are curved and slightly undercut as indicated at 147, Fig. 12^a in which 41 indicates the core, 148 the metal of the plate and 110 the matrix. This undercutting provides sufficient connection 80 between the cast plate and the core to enable it to be temporarily bent when the core collapses and to be transferred by the core to the boring shell, while still allowing it to be stripped from the core into the boring shell. 85 The matrix being clamped in the casting shell and the side gages locked as explained with reference to Figs. 13 and 14 and the core expanded and moved into position in the casting shell 22, the operation of the machine 90 is as follows:—starting from the commencement of the cycle, which begins with the cast plate: Assuming this plate to have been cast and to be solid enough to be manipulated, the machine is started by pushing over the 95 striking lever 39. The links 35 are in the position shown in Figs. 3 and 5, and because the center is slightly past (to the left in Figs. 3 and 5) the line joining the centers T and V the core is firmly locked in the casting position. 100 The center V cannot move further to the left because the train of gear 28 to 31 controlling it is stopped by the roller 45 which drives the boring shell 23 and which is now at the end of the groove in the drum 105 20. The shaft 36 is also eccentric with regard to the center of the casting shell 22, being so on account of the motion required to force the segments of the core apart into the proper casting position. As the crank wheel 110 32 and crank disk 34 begin to move in the direction of the arrow R, Figs. 3 and 5, the center T of shaft 36 moves towards a position concentric with the casting shell. When it arrives at this position the outer ends of the 115 slots 133 have moved up to the pins 132 and the brackets 134 have through the links 135 closed up the core as shown at position I in the diagram Fig. 15, dragging with it the newly cast plate 152, Fig. 15 which is thus 120 bent inwards away from the matrix at the top and bottom. The plate is now free from the matrix except in the vicinity of the hinge point 128. Further motion of the links 35 starts the core rolling and the plate finally 125 leaves the matrix, being rolled away by the action of the spur wheels 42 and segmental racks 43 through position II into the boring shell. So long as this rolling of the core continues, the shaft 36 remains concentric with 130

the core and shortly before the shaft 36 has completed the forward oscillation the plate rolls into the boring shell and under the fixed stopper bars 60 as explained the head of the 5 jet describing the curved path indicated by dotted lines 149. In the further forward motion of shaft 36 to complete the oscillation, the center T of the core shaft 36 again moves relatively to the core, which therefore 10 expands again with the plate bending it back to shape or approximately so and the gravity catches 142 fall into engagement with the noses 144 and stopper bar 59 which had been drawn back to allow free movement for the 15 plate, moves forward over the edge of the plate. Meanwhile the links 35 have come to the end of their stroke and the action is now reversed, the effect of which is to strip the plate from the core and to break off the jet. 20 The stripping of the plate from the core is effected by the stopper bars 58 and 60 which prevent the plate from rolling back with the core. The breaking of the jet is effected as indicated in Fig. 15 by the wedge shaped 25 mouthpiece component 115. This as the core rolls back describes the dotted path 150 and presses the jet down over the edge 151 of the boring shell at about the line of the sharp angles formed therein by the knife 116 and 30 gripper bar 112 so as to break it off, as shown at position III, Fig. 15. The core is prevented from collapsing in its return rolling motion by the gravity catches 142 which remain in engagement with the noses 144 and 35 fall out of engagement when the core has rolled back into the casting shell 22, in which position the brackets 134 keep it expanded ready for the next cast. While the core completes its return to the casting position the 40 boring shell 23 slides away to the boring position at the other end of the machine, the straight edges of the plate being trimmed by the tools in the boxes 46 as the boring bed slides under same. As soon as the core has 45 returned into the casting shell, *i. e.* on the completion of the back oscillation of shaft 33 the tripping mechanism described with reference to Figs. 7 to 10 comes into action to release the weight 96 which descends and the 50 pump delivers the molten metal into the mold for the next cast. Simultaneously with this last action the boring knife 52 begins to bore the plate in the boring shell and while this boring and the subsequent driving of the 55 plate round on the boring cylinder by the driver bar 53 are taking place the new cast is cooling in the casting shell. Almost immediately the plate is in position under the boring cylinder 47 the knife 52 which has al- 60 ready made a revolution since the commencement of the cycle, enters the shell and bores the plate, which is meanwhile held by the bar 59 which slides into position at the same time as the bar 58. On the completion of 65 the boring the projections 86^a of the driver bar

53 pass through the gaps 88^a of the delivery table 61 and come against the lower edge of the plate and drive it out of the boring shell round to a position J J Fig. 3 on the ribs 54 of the boring cylinder, the tools 57, 57 trimming the curved edges as the plate rotates. 70

The stopping mechanism before described now acts and operations cease, the cycle being complete. When the machine starts on a second cycle the plate is delivered on to the 75 table 61, the leading edge of the plate being prevented from further rotation by the projections 88 of the delivery table on to which it is pushed by the driver bar 53. When the bar 53 begins to rotate again at the commencement of a new cycle it will tilt the plate over on to the delivery table. It will thus be seen that while one plate is being finished another is being cast and that the cycle of the machine ends with a plate cast in the mold. 80 Thus while time is economized the attendant can always make sure that the cast plate has cooled and set sufficiently to bear manipulation before starting the machine in the cycle. 85

I will now describe the modified form of 90 collapsible core and its operating mechanism as illustrated in Figs. 16 to 19. This core consists of two segments 153, 153^a the upper of which carries the usual wedge shaped complement 115 for the mouthpiece and is hinged 95 as before, but with a different form of hinge. The members 154, 155 of this form have semi-circular bearing surfaces 156 both of which encircle the pin 157. To hold the 100 whole together, a split collar 158 is used, the pressure of which is adjusted by a screw 159. The shaft 160 of the core corresponds with, 105 the shaft 36 of the original arrangement and is carried by the links 35, 35 and connected to the spur wheel 32 and crank disk 34 as before except that the eyes by which the links 35 are connected to the studs 35^a on the wheel 32 and crank disk 34 are slightly slotted as at 160^a. In the present arrangement 110 however the shaft 160 is rigidly fastened in bosses 161, 161 of the lower segment. Spur wheels 42 mounted on the shaft 160 as in the previous arrangement effect the same rolling motion of the core by engaging similar racks 115 43, guides or bearing surfaces 162 being provided on the spur wheels so as to run on curved guides 163 on the racks (Fig. 18) to prevent the spur wheels and racks engaging 120 too deeply. 164 is a cam having a slot 165 and forms a path for the roller 167 which revolves freely on a stud 168 which projects through a slot 169, struck from the hinge center, in the spur wheel and guide. An identical arrangement of cam mechanism is provided at the other end of the core, the cams 125 being attached at each side to a link 170, these links being centered on a shaft 171 set in eccentric bushes 172 working in the frames 1 and 2. The weight 39 to balance the core is hung from this shaft by arms 40, 40 as before. 130

The eccentric bushes 172 are given an oscillating motion in their bearings so as to give the center of the shaft 171 and hence the links 170 and cams 164 a back and forth movement in a direction the average of which is along the line of the center of shafts 171 and 160. This is effected by a forked link 173 at each side connected to slotted arms 174 of the bushes 172 by a stud 175, the links 10 173 receiving their motion from cams 176 oscillating with the shaft 33 and actuating the forked links by cam grooves 177 and rollers 178. The core members are provided with registering grooves 145 at the hinge point for 15 the reception of asbestos or like packing. The arrangement of the remainder of the machine is as before described.

The action is as follows:—When the mechanism is in position for a cast, *i.e.*, when the 20 core is expanded, the center of the circular roller path 165 of cam 164 is further away from the center of curvature of the rack 43 than is the center of shaft 160. On starting the machine the eccentric bushes 172 come 25 into action and draw the shaft 171, links 170, cams 164, rollers 167 and segment 152 down till the upper portion of the plate is free from the matrix as far as the hinge point. The roller path 165 is now concentric with the 30 shaft 160 and the center of shaft 171 coincides with the center of curvature of the rack 43. The mechanism is now in a suitable position for the rolling of the plate into the boring shell. Meanwhile the studs 35^a on the 35 disk 34 and spur wheel 32 have moved from one end to the other of the slotted eyes 160^a and are about to drive the core away to deliver the plate through the medium of the links 35.

40 Fig. 19 shows the movements of the plate. The core is shown in position I, Fig. 5 (corresponding with Fig. 18) with the top segment 152 drawn down. The upper half of the plate 152 has been drawn from the matrix, which is omitted for the sake of clearness. As the core rolls out of the casting shell the lower half of the plate leaves the matrix at various points on the circumference in paths and directions indicated by 45 the dotted arrows. The velocities of these points are proportionate to the lengths of these paths and the action is such that if through any cause the plate tends to adhere to the matrix a tension is set up in the latter 50 from the point *f* upwards, thus keeping it taut in the region where such a strain is desirable at the time. The core and plate roll through position II into the boring shell 23 under the action of the mechanism described, 55 the head of the jet 152^a describing approximately the path 179 and rolling clear of the bottom edge of the boring shell 23. In the present case the core does not expand in the 60 boring shell 23, its operating mechanism acting to keep it collapsed until it is returning 65 into the casting shell. The plate is stripped from the collapsed core as in the original form of the machine and as the core begins to roll back out of the boring shell 23 the jet is broken off over the bottom edge of the shell 70 by the wedge shaped mouthpiece component 115 as previously described, this describing the path 180 which crosses the path 179 of the jet. Shortly before the core completes its return roll into the casting shell the 75 straight portion of the cam grooves 177 rocks the forks 173 and shaft 177 so that the cams 164 lift the top segment of the core and expand the same into the casting position.

Instead of collapsing the core to bend the 80 plate for the purpose of stripping it from a fixed matrix I may attain the same object with a non-collapsible core adapted to be moved or rolled into and out of the casting box. I effect this object by providing means 85 whereby during the initial portion of the movement of the core in quitting the casting box the cast plate adhering thereto is prevented from following the movement of the core so that clearance for bending the plate 90 on the core is created, the plate being bent inwards by appropriate means so that it will strip from the matrix without injury thereto and then moving out with the core. An example of such an arrangement is shown in 95 Figs. 20 to 22 applied to the machine of Figs. 1 to 15.

22 is the casting shell in which the matrix is rigidly clamped. 181 is a cylindrical core to which are fixed at each end the toothed 100 wheels 182 and circular guides 183 arranged to run on the segmental racks and guides 184, 185 on the main frame as before. The core is mounted on a shaft 186 carried by links 187, 187 corresponding to the links 35 of the 105 first described arrangement and driven in the same way by the oscillating spur wheel 32 and crank disk 34. 38 are levers connecting the counterweighted central shaft 37 as before. By this means the core 181 can be 110 rolled into and out of the casting shell 23 on the racks and rails in a manner similar to that already described.

The mouthpiece of the mold is made up of a plate 188 carried by the casting shell 22 and 115 extending the full width of the core, a corresponding wedge shaped component 189 fixed to the core and end pieces 190 adapted to slide on the core as explained later. The plate 188 serves as the gripper to hold the 120 matrix at its top edge. It is mounted on the shaft or stay 191 so that it can be turned thereon for inserting and clamping the matrix and retained in its released or clamping positions by any suitable means. The bottom edge of the matrix is similarly clamped by the pivoted gripper bar 188^a and the means for clamping the matrix are otherwise similar to those in Figs. 13 and 14.

The sliding end pieces 190 are attached by 130

their spigots 192 to arms 193 centered on the core at 194 and coiled springs 195 on spigots 192 tend to keep the end pieces 190 pressed against the core when the mold is being closed, so that the several parts of the mouth-piece come together in their proper relative positions. The arms 193 are guided and limited in their motions by the guides 196. The core also carries a fixed stopper bar 197 adapted to close the bottom of the casting space; the bar is formed with a projecting feather 198. This feather projects into the lower edge of the cast plate so as to hold it on the core during the rolling out, but not so much as to prevent the plate being wrenched clear when it is being stripped off into the boring shell as explained.

199, 199 are catches mounted on the stay 191 and kept pressed downwards by coiled springs 200 into position to engage projections 201 on the sliding end pieces 190 so as to hold these in position when the mold core is in casting position and retain them during the initial portion of the outward rolling motion of the core until they are automatically released by the action of the arms 193. To prevent the spring 200 forcing the catches 199 too far round, these latter have shoulders 202 which abut against shoulders on the bosses 203 which carry the stay 191. The sliding end pieces 190 are formed with inwardly projecting edges 204, so that when the metal is poured corresponding shoulders or recesses are cast in the plate at these points, these abutting against the ledges 204 to permit bending of the plate as about to be explained.

The operation is as follows:—The plate having been cast as described and the machine started on its cycle the core begins to roll out of the casting shell 22 under the action of the links 187 spur wheels 182 and racks 184, the projections 201 being still held by the catches 199 so that the end pieces 190 do not follow the rolling motion of the core which begins to roll out under them thus creating clearance between the core and matrix. The motion of the center 194 in this initial rolling has a downward motion such that the arms 193 draw the end pieces 190 down parallel with the engaging faces of the catches 199 carrying with them the cast plate by means of the projecting ledges 204 which at the same time serve as an abutment for the cast plate. As the rigidly fixed stopper bar 197 rolls with the matrix the result of these combined motions is that the straight edges of the plate are bent inwards on the core away from the matrix during the initial portion of the rolling, the end pieces 190 stripping the upper portion of the plate from the matrix and the stopper bar 197 stripping the lower portion of the plate therefrom, moving it off in a direction at approximately right angles to a tangent to

the circumference of the mold. The catches 199 serve to keep up the described relative motion of the core and end pieces 190 till the plate has been stripped from the matrix, when the projections, 201 move beyond the control of the catches 199. By this time the inner ends of the guides 196 have come against the arms 193 and the arms 193 are driven with the core, so that the core rolls away with the plate as indicated in Fig. 22. The core delivers the plate into the boring bed and the other operations of the machine are as previously described, the core meanwhile rolling back into the casting position with the projections 201 engaged by the catches 199.

To relieve the catches 199 from the first strain of freeing the core from the plate recessed noses 205 (see Figs. 22 and 22¹) rigidly connected to the fixed stay 191 may be provided and arranged to project into the part of the casting space where the head piece is formed, so that projections 206 are cast in the head piece. These projections not being so high as the projection 201 will be quite clear of the noses 205 before the plate begins to move away the control, after the first strain is over, being taken by the catches 199. As a rule the projections 199 will be well clear of the catches 201 before the guides 196 begin to drive so that both ends of the core will be able to move away at the same time so as to keep the plate parallel, but for finer adjustment instead of the steps 202, 203 the catches 199 may be provided with a slotted extension 207 through which an eyebolt 208 carried by a stud in the shell of the mold would pass the adjustment being provided by lock nuts 209 against which the extension 207 would press.

It will be evident that the method of stripping a curved stereotype plate from a fixed matrix by bending the plate on the core and providing clearance to permit this bending may be applied with advantage not only to machines for automatically casting or automatically casting and finishing curved stereotype plates but to machines in which such plates are cast and finished partly or entirely by hand.

By way of example I have illustrated in Fig. 23 the arrangement of Figs. 20 to 22 applied to a stereotyper's hand box. The arrangement of the casting shell and the means for clamping the matrix in position and bending of the plate on the core during the rolling out of the same are the same as in the last described arrangement similar letters of reference indicating corresponding parts. 22 is the casting shell as before and 210 the core. In this case the rails and racks upon which the core is arranged to roll out are straight as indicated at 211, 212, the core being provided with corresponding toothed sectors and segmental guides 213, 214. The core is rolled in

and out by a Stanhope lever locking arrangement consisting of links 215 and levers 216 at each side of the core. The shaft 217 of the core is mounted in the links 215 which are jointed to the levers 216, these being fixed on a shaft 218 which is turned by the operator by ordinary means such as a crank handle 219.

When the plate has been cast and allowed 10 to cool, all that is necessary is to turn the shaft 218 in order to unlock the casting box, bend and strip the plate from the fixed matrix and roll it away on the racks and rails in a similar manner to that described with reference 15 to the preceding arrangement, the plate rolling into a convenient position to be removed from the core by the operator.

It will be evident that the method of bending and stripping the plate from a fixed matrix by using a collapsible core can likewise be applied to manually operated curved stereotype casting apparatus. For example 20 the casting box, collapsible core and its operating mechanism described with reference respectively to the two first described forms of 25 machine can be applied to or employed as a hand casting machine by simply employing two crank disks 34 for connection to the links 35 and turning the shaft 33 by hand.

Many other forms of mechanism for effecting 30 the bending of the plate on the core and stripping it from a fixed matrix can be devised by those skilled in the art and various other means for collapsing the core to bend and 35 strip the plate will suggest themselves. When a collapsible core is employed it may consist of more than two hinged segments if desired.

In carrying the present invention into effect 40 the cores or their segments should be made hollow and cooled by a circulation of water or other medium and the casting and boring backs can also be similarly cooled. This can be done by any means ordinarily 45 employed for the purpose. The different parts of the machine and the jet of the plate may also be cooled by expanding or liberating compressed air in the hollow core or casting and boring backs or other desired part of 50 the machine.

I have found that the bending of the plate as described has no detrimental effect from the printing point of view, and moreover the plate is restored or approximately restored to 55 true shape in the boring operation if this has not been already effected on the core.

While in the practical application of the present invention I prefer to employ a fixed matrix and to strip the cast plates successively therefrom in a manner such as described, it is to be understood that the invention is not restricted thereto and that certain of the improved combination of elements 60 may be employed in other forms of apparatus for producing curved stereotype plates.

In particular the invention broadly comprises the combination with a casting box or mold of a boring bed adapted to be moved alternately into a position for the reception of a cast plate from the mold and into a suitable position for the boring of the plate together with a core arranged and actuated to move between the mold and boring bed and to deliver the cast plate direct from the mold into the boring bed.

What I claim and desire to secure by Letters Patent is:—

1. In a machine for casting curved stereotype plates, a curved mold and a core adapted to be moved into and out of same, means for fixing a matrix in the mold means for bending the cast plate inwards on the core and means for moving the core with the plate thereon out of the mold to strip the plate from the fixed matrix. 80

2. In a machine for casting curved stereotype plates, a curved mold and a core adapted to be rolled into and out of the mold, means for fixing a matrix in the mold, means for bending the plate inwards on the core and 90 means for rolling the core with the plate thereon out of the mold to strip the plate from the fixed matrix. 85

3. In a machine for casting curved stereotype plates, a curved mold and a collapsible core coacting therewith, means for fixing a matrix in the mold, means for collapsing the core and bending the plate inwards thereon and means for moving the collapsed core with the plate thereon out of the mold to 100 strip the plate from the fixed matrix. 95

4. In a machine for casting curved stereotype plates, a curved mold and a collapsible core coacting therewith, means for fixing a matrix in the mold, means for collapsing the core and bending the plate inwards thereon and means for rolling the collapsed core with the plate thereon out of the mold to strip the plate from the fixed matrix. 105

5. In a machine for casting curved stereotype plates, a curved mold and a core coacting therewith and composed of collapsing segments, means for fixing a matrix in the mold, means for collapsing the core, means for providing connection between said core 115 and the cast plate, whereby when the core collapses the plate is bent inwards thereon and means for rolling the collapsed core and plate out of the mold to strip the plate from the fixed matrix. 110

6. In a machine for casting curved stereotype plates, a curved mold and a core coacting therewith and composed of hinged segments, means for fixing a matrix in the mold, a shaft on which said core is mounted, gear 125 wheels on said shaft, racks with which said gear wheels mesh, means for collapsing the core, means for providing connection between the core and the cast plate whereby when the core collapses the plate is bent in- 130

wards thereon and adheres thereto and means for rolling the core into and out of the mold by the engagement of said racks and gear wheels, whereby when the collapsed core is rolled out of the mold the plate is stripped from the fixed matrix.

7. In a machine for casting curved stereotype plates, a curved mold and a core coacting therewith and composed of hinged segments, means for fixing a matrix in the mold, a shaft on which said core is mounted, gear wheels on said shaft, racks with which the gear wheels mesh, arms carrying said shaft, means for imparting vibrating motion to said arms whereby the core is rolled into and out of the mold by the engagement of said racks and gear wheels, means for collapsing the core before it leaves the mold, and for subsequently expanding it, and means for providing connection between the core and cast plate whereby when the core collapses the plate is bent inwards thereon and adheres thereto and is stripped from the fixed matrix by the core as it rolls out of the mold.

8. In a machine for casting curved stereotype plates, a curved mold and a core coacting therewith and formed of upper and lower hinged segments, means for fixing a matrix in the mold, a shaft on which said core is mounted and which is fixed to the lower segment, gear wheels on said shaft, segmental racks with which the gear wheels mesh, arms carrying said shaft, means for imparting vibrating motion to said arms whereby the core is rolled into and out of the mold by the engagement of said racks and gear wheels, cam disks carried by said arms, cam rollers on the upper core segment coacting therewith whereby the core is collapsed before leaving the mold and subsequently expanded by casting the next plate and means for providing connections between the core and cast plate, whereby when the core collapses the plate is bent inwards thereon and adheres thereto and is stripped from the fixed matrix by the core as it rolls out of the mold.

9. In a machine for casting curved stereotype plates a curved mold, top, bottom and side gages adapted to rigidly hold a matrix in said mold, means for securing said gages in position to hold the said matrix, a core and means for bending a plate cast in said mold inwards on said core, stripping it from said fixed matrix and withdrawing it from the mold.

10. In a machine for casting curved stereotype plates, a curved mold, side gages fitting therein and adapted to retain the sides of a matrix in the mold, top and bottom gages adapted to be turned to release and clamp the top and bottom edges of said matrix in the mold, means for locking said gages in their clamping position, a core and means for

bending a plate cast in said mold, inwards on the core, stripping it from the matrix clamped by the gages and withdrawing it from the mold.

11. In a machine for casting curved stereotype plates, a curved mold, clamping side gages fitting therein and adapted to retain the sides of a matrix in the mold, hinged top and bottom gages adapted to be turned to release and clamp the top and bottom edges of said matrix in the mold, and a mold impinge boring adapted in its clamping position to lock the side gages in clamping position, eccentric gear for turning said top and bottom gages into and out of clamping position, a core and means for bending a plate cast in said mold so inwards on the core, stripping it from the matrix clamped by the gages and withdrawing it from the mold.

12. In a machine for casting and boring curved stereotype plates, a curved mold, a boring bed and a core adapted to be moved into casting position in said mold, in combination with means for moving said core with the cast plate thereon direct from the mold into the boring bed to deliver said plate thereinto.

13. In a machine for casting and boring curved stereotype plates, a curved mold, a reciprocating boring bed and a core adapted to be moved from the mold direct into the boring bed and conversely, in combination with means for so moving the core with the cast plate thereon direct from the mold into the boring bed to deliver said plate thereinto.

14. In a machine for casting and boring curved stereotype plates, a mold, a reciprocating boring bed adapted to move into boring position and to move into a position opposite said mold, and a core in combination with means for moving the core with the cast plate thereon direct from the mold into the boring bed to deliver the plate thereinto and means for returning the core from the boring bed into the mold.

15. In a machine for casting and boring curved stereotype plates, a stationary curved mold, a reciprocating boring bed adapted to move alternately into a position of rest opposite said mold and into boring position, and a core in combination with means for swinging the core with the cast plate thereon direct from the mold into the boring bed to deliver the plate thereinto and for swinging the core back from the boring bed into the mold.

16. In a machine for casting and boring curved stereotype plates, a curved mold, a reciprocating boring bed adapted to move alternately into a position opposite said mold and into boring position in combination with a core adapted to be moved direct from the mold into the boring bed and conversely, means for so moving the core with the cast plate thereon direct from the mold into the

boring bed and stripping devices for stripping the cast plate from the core into the boring bed.

17. In a machine for casting and boring 5 curved stereotype plates, a curved mold, a horizontally reciprocating boring bed and means for reciprocating the same alternately into a position opposite the mold and into a position for the boring operation, a core, 10 means for moving the core direct from the mold into the boring bed and conversely, to deliver a cast plate into the boring bed and to return to casting position, a stripping device and means for operating the same to admit 15 the plate on the core to the boring shell and to thereafter engage a straight edge of the plate and strip it thereinto from the core on the return motion of the core from the boring shell and means for engaging the plate at the 20 opposite edge and retaining it in the boring shell.

18. In a machine for casting and boring curved stereotype plates, a curved mold, means for fixing a matrix thereon, a boring 25 bed, means for moving the same alternately into a position near the mold and into boring position, a movable core, means for bending the cast plate thereon and stripping it from the fixed matrix and for operating the core 30 to deliver the cast plate direct from the mold into the boring shell.

19. In a machine for casting and boring curved stereotype plates, a curved mold, means for fixing a matrix therein a reciprocating 35 boring bed, mechanism for moving the same alternately into a position opposite the mold and into boring position, a movable core and means for bending and retaining the cast plate thereon and stripping it there- 40 on from the fixed matrix, means for rolling the core with the cast plate direct from the mold into the boring bed and for delivering the plate thereinto and means for returning the core into the mold.

45 20. In a machine for casting and boring curved stereotype plates, a curved mold, means for fixing a matrix therein, a reciprocating boring bed, mechanism for moving the same alternately into a position opposite 50 the mold and into boring position, a collapsible core, means for providing connection between the same and the cast plate, mechanism for collapsing the core after the casting operation to bend and strip the plate on the 55 core from the fixed matrix and means for rolling the core with the cast plate thereon direct from the mold into the boring bed to deliver the plate thereinto, and means for expanding and returning the core into the mold 60 for the succeeding cast.

21. In a machine for casting and boring curved stereotype plates, a curved mold, a core adapted to move into said mold and out of same to deliver a cast plate therefrom, a

reciprocating boring bed and mechanism for 65 moving the same alternately into position to receive the plate from said core and into a position for the boring of the plate, means for operating the core to deliver the plate direct from the mold into the boring bed, and means for breaking off the jet from the plate in the boring bed prior to the travel thereof to the boring position.

22. In a machine for casting and boring curved stereotype plates, a curved mold, a horizontal reciprocating boring bed adapted 75 to move alternately into a position of rest opposite said mold and into a position of rest for the boring operation, a core, means for moving the same direct from the mold into 80 the boring bed to deliver the cast plate thereinto and for returning the core into the mold, a stripping device and means for operating the same to admit the plate and the core to the boring bed and to thereafter engage the 85 straight edge of the plate at the opposite side to the jet and strip the plate into the boring bed from the core, retaining devices between which the jet of the plate is located when delivered into the boring shell and adapted to engage the plate at each side of the jet to retain the plate in the boring bed and a projecting member on the core adapted to press upon the jet as the core returns from the boring bed and thereby break off the jet to enable the plate to slide with the boring bed to the 90 boring position.

23. In a machine for casting and boring curved stereotype plates, a curved mold, a reciprocating boring bed, horizontal guides 100 whereon said bed travels, mechanism for reciprocating said bed thereon alternately into a position of rest opposite the mold and into a position of rest under a rotating boring bed and delivery cylinder, a core and means 105 whereby the same is rolled and swung with the cast plate direct from the mold into the boring bed to deliver the plate thereinto and back from the boring bed into the mold, a retaining stripping device automatically operated to allow the plate and core to roll and swing into the boring bed and to thereafter engage the straight edge of the plate at the 110 opposite side to the jet and strip the plate into the boring bed from the core on the return of the core, retaining devices between which the jet of the plate is located when delivered into the boring shell and adapted to engage the plate at the sides of the jet to retain the plate in the boring bed, a projecting 115 member on the core adapted to press the jet down over an edge of the boring shell in the return roll and swing of the core and thereby break off the jet to enable the plate to slide with the boring bed under the last mentioned 120 retaining devices, means for retaining the plate in the boring bed in the boring position, a boring tool and a driving member on said 125

boring and delivery cylinder adapted to respectively bore the plate and drive it round out of the boring bed, substantially as described.

24. In a machine for casting and boring curved stereotype plates, a curved mold, a reciprocating boring bed, horizontal guides whereon said bed travels, mechanism for reciprocating said bed thereon alternately into 10 positions of rest respectively opposite the mold and under a rotating boring and delivery cylinder, a core and means whereby the same is moved with the cast plate direct from the mold into the boring bed to deliver the plate thereinto and back from the boring bed into the mold, means for retaining the plate in the boring bed when delivered thereinto by the core, means for breaking off the jet from the cast plate in the boring bed, devices for retaining the plate in the boring bed in the boring position, a boring tool and a retractable driving member on said boring and delivery cylinder adapted to respectively bore the plate and drive it round out of the 20 boring bed, and mechanism for automatically retracting said driving member to clear the plate until the boring tool has acted thereon and thereafter protruding it to driving position, substantially as described.

25. The combination in a machine for casting and finishing curved stereotype plates of a curved mold, a reciprocating boring bed, horizontal guides whereon said bed travels mechanism for reciprocating said bed thereon alternately into positions of rest 30 respectively opposite the mold and under a rotating boring and delivery cylinder, a core and means for moving the same with the cast plate direct from the mold into the boring bed to deliver the plate thereinto and back from the boring bed into the mold, means for stripping the plate from the core into the boring bed and retaining it therein, means for breaking off the jet from the cast plate in the boring bed, devices for retaining the plate in the boring bed in the boring position, a boring tool and a retractable driver on said 40 boring and delivery cylinder adapted to respectively bore the plate and drive it round out of the boring bed, and mechanism for automatically retracting said driving member to clear the plate until the boring tool has acted thereon and thereafter protruding it to driving position, substantially as described.

26. In a machine for casting and boring curved stereotype plates, a fixed casting mold, horizontal guides disposed parallel thereto, a boring bed arranged to travel thereon, a drum parallel to said mold and supporting the boring bed, and driven alternately in opposite directions, a cam groove in said drum whereby the boring bed is reciprocated alternately into a position of rest

opposite the mold and into a position of rest 65 below a rotative boring and delivery cylinder, a core and mechanism for moving the same direct from the mold into the boring bed to deliver the cast plate thereinto when the boring bed is opposite the mold and for 70 moving the core back into the mold during the travel of the boring bed to the boring position, and means for rotating the boring and delivery cylinder to bore and deliver the plate. 75

27. In a machine for casting and boring curved stereotype plates, a fixed casting mold, a boring bed adapted to reciprocate parallel thereto into positions of rest respectively opposite the mold and under a boring 80 device, said boring device, a core and mechanism for moving the same direct from the mold into the boring bed to deliver the cast plate thereinto when the boring bed is opposite the mold and for thereafter moving the core back into the mold and means for reciprocating the boring bed and arresting it in its said respective positions, substantially as described.

28. In a machine for casting and trimming curved stereotype plates, the combination with a mold, a melting pot and a weight-operated pump, of a rocking shaft, a cord pulley loose thereon, a cord connected to said pulley and to the weight of the pump, a 95 driver fast on the shaft, pins on said driver and a stop on said cord pulley adapted to be engaged by one of said pins to drive the pulley round to wind up the cord and lift the pump weight, a catch adapted to engage said 100 stop and thereafter to be released by the other of said pins in the return oscillation of the rocking shaft, whereby the pulley is released and the pump weight is allowed to descend and force the metal into the mold, substantially as described. 105

29. In a machine for casting curved stereotype plates, the combination of a curved mold, a core, means for bending the plate inward, and means for separating the plate and mold. 110

30. In a machine for casting curved stereotype plates, the combination of a curved mold, a core, means for bending the plate inward on the core, and means for separating the core and plate from the mold. 115

31. In a machine for casting curved approximately semi-circular stereotype plates or the like, the combination of a mold, a matrix fixed therein, and means for separating the plate from the matrix without removing the latter from the mold. 120

32. In machines for casting stereotype plates or the like, the combination of a curved mold, a curved matrix fixed therein, 125 and means for separating the plate from the matrix while the latter is in the mold without injuring the matrix.

33. In machines for casting curved stereotype plates or the like, the combination of means for boring one plate and simultaneously casting and cooling a succeeding plate, and a core adapted to automatically transfer a plate from the casting to the boring position.

In witness whereof I have hereunto signed my name in the presence of two subscribing witnesses.

ROBERT CUMMING ANNAND.
